GUN MOUNT

Daniel S. Elliott, Middle River, Md., assignor to
The Glenn L. Martin Company, Baltimore,
Md.

Application September 24, 1940, Serial No. 358,044

1 Claim. (Cl. 89—37.5)

The invention relates to mounting means, and particularly mounting means for guns such as machine guns.

A primary object of the invention is to provide a collapsible tripod mounting means which gives secure support to a gun or the like when in raised position, and which can be collapsed to a position in which it occupies little space.

A further object of the invention is to provide a mount of this type which can be collapsed without the removal of the gun therefrom, so that it may be easily and quickly installed in an operative position without the necessity of reattaching the gun thereto.

Another object of the invention is to provide a mount which can be collapsed onto the floor of a compartment in which it is mounted, while holding the gun attached thereto.

Still another object of this invention is to provide a gun mount which is capable of holding a gun with it in collapsed position, or of locking a gun in a stationary condition thereon when the mount is raised, or of holding the gun in a universally movable relation to permit manipulation and aiming thereof.

Still a further object of the invention is to provide a mount of this type with a simple means for removing the gun therefrom.

An additional object of the invention is to provide a mount of this type which holds the gun in a stationary, stowed position when it is upright, with means for quickly releasing the gun for manipulation, this means comprising a single locking member which can be operated by a hand lever.

Further objects and advantages of the invention will appear more fully from the following description partially when taken in conjunction with the accompanying drawings which form a part thereof.

In the drawings:

Fig. 1 is a side elevation of a gun mount embodying my invention;

Fig. 2 is a front view thereof;

Fig. 3 is an enlarged detail principally in section through the swivel joint and connection between the gun and the mount;

Fig. 4 is a cross section on the line 4—4 of Fig. 3; and

Fig. 5 is a view similar to Fig. 4 with the parts in released position.

As shown in the drawings, the gun indicated generally at 2 is to be mounted preferably within a compartment having a floor indicated at 4. The gun mount includes a V-shaped member or

strut having legs 6 connected by pivots 8 to projections 10 from the floor 4. At its upper end the V-shaped member has an enlarged tubular portion 12 provided with a projection 14 on the rear side. This projection carries a pivot 16 on which is engaged one end of a link 18 which extends downwardly and rearwardly. The lower end 20 of link or strut 18 is formed to engage within a U-shaped frame 22 secured to a fixed part 24 of the structure. The legs of the U-shaped portion 22 and of the end 20 are provided with holes which can be brought into registration, so that a pin 26 having a handle 28 can be inserted therethrough. Thus the link 18 may be held in a position to support the V-shaped main frame member.

The gun 2 is pivoted to turn about a vertical axis on pins 30 mounted in the ends of a U-shaped member 32. The bight 34 of this U-shaped member is pierced by a headed block 36 (Fig. 3), thus forming a pivot for the frame 32 about a vertical axis.

Block 36 extends into the end of tubular portion 12, and is provided therein with annular groove 38. This groove is positioned opposite to balls 40 mounted in holes 42 in the wall of the tubular section 12. A sleeve 44 is mounted to turn on the outside of the tubular section 12, being prevented from slipping off the end thereof by an inwardly turned flange 46 engaging in a groove in section 12. The sleeve 44 has cam shaped grooves 48 of gradually increasing depth opposite the balls 40.

When the parts are in the position shown in Fig. 5, the balls 40 are able to move into the deeper ends of grooves 48 and thus out of the grooves 38 in the block 36. Thus the block may be removed with the U-shaped member. On the other hand, if sleeve 44 is turned to the position shown in Fig. 4 the shallow parts of the grooves 48 force the balls into groove 38 and thus lock the block 36 to the V-shaped frame.

Likewise pivoted on the pin 16 is a lever arm 50 having at its end a jaw 52 provided with a partly circular recess. Pivot at 54 on lever 50 is a cooperating lever having a handle portion 56 on one side of the pivot and a jaw portion 58 provided with a partly circular recess cooperating with the recess in the jaw portion 52. A flat leaf spring 60 rests against lever 50 on one side of the pivot 54 and against the back of jaw portion 58, thus urging jaw portion 58 towards jaw portion 52. The gun is provided with a pin 62 adapted to be enclosed between jaw portions 52 and 58.

When the parts are in the position shown in solid lines in Fig. 1, the gun is in a raised but stowed position. Because of the engagement of lever 50 with pin 62, the gun is incapable of moving and is therefore held stationary.

If the gun is to be operated, lever 56 is pushed towards lever 50 so as to move jaw 58 and release the pin 62. Lever 50 is then dropped to the broken line position shown in Fig. 1.

In this position the gun is left free to turn about axis 30 and swivel block 36, so as to have a universal movement.

In order to collapse the whole mount, pin 26 is removed. The V-shaped frame 6 may then swing downwardly to the position shown in broken lines in Fig. 1 and in such position the lever 18 collapses between the legs of the V-shaped member. The gun also can lie substantially flat on the floor 4 in such collapsed position.

While I have described herein one embodiment of my invention, I wish it to be understood that I

do not intend to limit myself thereby except within the scope of the appended claim.

I claim:

5 In combination with a supporting structure, a gun mount of tripod form comprising an inverted V-shaped strut and a single rigid strut, pivotal means on the apex of said V-shaped strut constructed and arranged to support a gun, pivots connecting the ends of the legs of said V-shaped strut to said supporting structure for collapsing movement thereagainst, an additional pivot connecting one end of said single strut to the apex portion of said V-shaped strut for pivotal movement about an axis parallel to the pivotal axis 10 of the V-shaped strut, lever means having a common pivot with the single strut for locking the gun against movement on the mount, and a readily removable pin extending through the other end of said single strut and into a portion of the 15 supporting structure for maintaining the gun mount rigidly in its uncollapsed tripod form.

DANIEL S. ELLIOTT.
